UNITED STATES PATENT OFFICE.

JOSEPH R. HOLLAND, OF BINGHAMTON, NEW YORK, ASSIGNOR OF TWO-EIGHTHS TO EDWARD W. DUGDALE, OF KEARNEY, NEW JERSEY, AND FIVE-EIGHTHS TO CHARLES H. BUCK, OF BINGHAMTON, NEW YORK.

HORSESHOE.

No. 799,850.

Specification of Letters Patent.

Patented Sept. 19, 1905.

Application filed August 26, 1904. Serial No. 222,268.

To all whom it may concern:

Be it known that I, JOSEPH R. HOLLAND, a citizen of the United States, residing at Binghamton, New York, have invented certain new and useful Improvements in Horseshoes, of which the following is a specification.

My invention relates to horseshoes of that type in which the calks are made removable, and has for its object the production of a shoe 10 of this type in which the calks may be easily secured and removed, but when once in place will be firmly held and will not become loose.

With this object in view my invention consists of the construction hereinafter described, 15 and more particularly pointed out in the claims.

In the accompanying drawings, Figure 1 is a bottom plan view of a horseshoe embodying my invention. Fig. 2 is a detail view of one 20 of the calks. Fig. 3 is a sectional view on the line xx of Fig. 1, showing the toe-calks in place. Figs. 4, 5, and 6 show a modified form of fastening device.

In the figures, A indicates the horseshoe, 25 which is of the same general construction as the shoes now in common use except that it is made without calks and at the points where the calks are usually placed, is provided with threaded holes a .

The calks B, B', C, and D may be either 30 square for ordinary use or they may be sharpened for icy weather, and are provided on the upper side with the threaded lugs b , which are adapted to enter the holes a of the shoe.

The upper face of the calk is also provided 35 with recesses c on opposite sides of the lug b , into which the wedge d is driven to prevent the calks from turning and becoming loose.

For the toe of the shoe I employ a double or 40 two-piece calk, each piece of which is screwed separately to the body of the shoe. In order that these calks may be screwed into the shoe and have their ends closely abutting without the ends interfering and binding, I make the 45 ends of the calks round, preferably making them to conform to the segment of a circle described from the center of the lug b .

As will be seen from the foregoing description, the toe-calks may be easily screwed into place, and when in the proper position their ends will abut, forming practically a continuous calk. The wedge d being driven into the recess between the two pieces prevents their turning. This wedge extends beyond the inner edge of the shoe and is turned up 55 and clenched.

By providing the calks with the wedge recesses in each end and making both sides of the calk alike it is possible to screw the calk much tighter into shoe, inasmuch as it is 60 only necessary to give it a half of a revolution to bring it in a locking position, whereas as a calk provided with a recess on one end only must be given a complete revolution before the wedge can be entered.

In Figs. 4, 5, and 6 I have shown a modified form of fastening device to be used with a single calk having the recesses formed in the opposite ends thereof. This fastening device consists of a washer L, preferably 70 rectangular in shape, having a lug l . The opening in the washer is of such dimensions as to fit the rectangular projection m , formed on the calk by cutting out the recesses c . When the calk has been screwed into place, 75 the lug l , which projects over the inner side of the shoe, is bent down, thereby locking washer and calk securely in place.

Having described my invention, what I 80 claim is—

1. In an article of the class described the combination with the horseshoe having openings therein of a pair of calks provided with lugs adapted to enter said openings, said calks having their abutting ends rounded and means 85 for holding said calks in fixed relation one to the other, substantially as described.

2. In an article of the class described the combination with the horseshoe having threaded openings therein, of a pair of calks each 90 provided with a threaded lug adapted to enter one of said openings, said calks being placed in alignment and having their ends conformed to segments of a circle described

from the center of said lug and means for holding said calks in alinement, substantially as described.

3. A removable calk for horseshoes comprising two sections, the front and rear sides thereof being alike, and the opposite ends thereof conforming to the segments of a circle described from the center of the calk and

means for securing the calk to the shoe, substantially as described.

In testimony whereof I affix my signature in presence of two witnesses.

JOSEPH R. HOLLAND.
